(57) **CLAIM**

The ornamental design for a portable electrical charger, as shown and described.

DESCRIPTION

FIG. 1 is a front bottom perspective view of a portable electrical charger shown in a folded, closed configuration.

FIG. 2 is a rear top perspective of the portable electrical charger shown in FIG. 1.

FIG. 3 is a front elevational view of the portable electrical charger shown in FIG. 1.

FIG. 4 is a rear elevational of the portable electrical charger shown in FIG. 1.

FIG. 5 is a right side elevational view of the portable electrical charger shown in FIG. 1.

FIG. 6 is a left side elevational view of the portable electrical charger shown in FIG. 1.

FIG. 7 is a top plan view of the portable electrical charger shown in FIG. 1.

FIG. 8 is a bottom plan view of the portable electrical charger shown in FIG. 1.

FIG. 9 is a rear perspective of the portable electrical charger shown expanded into a stand configuration.

FIG. 10 is a right side elevational view of the portable electrical charger shown in FIG. 9.

FIG. 11 is a rear elevational view the portable electrical charger shown in FIG. 9.

FIG. 12 is rear perspective view of the portable electrical charger shown with the lower lid in an open configuration.

FIG. 13 is a rear elevational view the portable electrical charger shown in FIG. 12; and,

FIG. 14 is a right side elevational view of the portable electrical charger shown in FIG. 9.
